UNITED STATES PATENT OFFICE.

LENA H. TAYLOR, OF LONGMEADOW, MASSACHUSETTS.

INFANT'S HOSE.

1,161,548.

Specification of Letters Patent. Patented Nov. 23, 1915.

Application filed October 1, 1914. Serial No. 864,398.

To all whom it may concern:

Be it known that I, LENA H. TAYLOR, a citizen of the United States of America, residing at Longmeadow, county of Hampden, and State of Massachusetts, have invented certain new and useful Improvements in Infants' Hose, of which the following is a specification.

My invention relates to improvements in infants' hose.

The objects of the present invention are—first, to produce an infant's hose of such a shape or form that it will permanently remain in place after it has once been secured; second, to provide a hose that is comfortable for the child by permitting freedom and action of the limbs and also one that can be kept sanitary and clean; third, to provide a hose that can be directly and quickly attached to the lower border of the infant's vest or shirt, thereby preventing the same from working upward or out of place and, at the same time, retaining the hose in its original position or place.

The usual manner of attaching an infant's hose is to pin the same to the napkin. This practice is objectionable for the reason that as the usual length of the hose is too long, it results in forming an uncomfortable bunch where the hose is attached. This practice is further objectionable in that it is necessary to remove the hose or unpin the same every time the napkin is changed. On account of the extra length of the hose, it soon becomes untidy. The present invention is, therefore, designed to overcome these various objections in infants' hose as now usually constructed. The above objections are successfully overcome by cutting away or removing the upper rear portion of the leg-member, leaving only a narrow integral strip or extension at the front portion thereof which extends the original length of the hose. The upper end of this extension part is designed to be pinned or otherwise secured to the lower border of the child's vest with the result that both the hose and vest are properly retained in position.

Referring to the drawings, Figure 1 shows the hose in position, clearly illustrating the extension part or strip at the forward part of hose that is designed to be attached at its end to the lower border of the vest. Fig. 2 is a detail view of the improvement showing clearly in side elevation the cut-away portion and the extension strip.

Referring to the drawings in detail, 1 designates the foot and 2 the leg members or portions of an infant's hose.

5 is an extension of the leg member which 60 is the same in length as the usual hose and indicated in dotted lines at 2' in Fig. 2. The rear portion of the leg part of the hose is cut away or removed at the point 4, which point is substantially one-half of the usual 65 length of the leg member of the hose. This part of the hose will, of course, be omitted when the hose is knit, leaving only the extension part 3 from the point 4 integral with the leg 2. The borders 5 and 6 are finished 70 in order to prevent them from unraveling.

6 designates the usual infant's vest, and, in order to permanently retain the hose in place, that is, to prevent its slipping down, the upper end of the extension 3 is attached 75 by means of a safety pin, or otherwise, to the lower border of the vest or shirt 6, as indicated at 7. A napkin is shown at 8 to which the upper end of the hose is usually connected.

It will be clearly seen from this construction of infants' hose that, by removing the upper rear part of the leg member, the infant is afforded perfect freedom of action of the limbs. The hose itself, as a whole, is 85 at all times maintained in a tidy and clean condition. It will also be apparent that by attaching the narrow extension part 3 to the lower border of the vest or shirt instead of to the napkin that the hose is easily retained 90 in place, and also the vest is, in turn, prevented from working upward out of its proper place as it oftentimes does. It will, therefore, be seen that I have provided a garment for infants' wear that is easily and 95 cheaply made and one that accomplishes its intended results, namely, comfortability, cleanliness, adjustability with relation to the infant's vest and, at the same time, prevents the child from displacing the same. 100

As heretofore explained and pointed out, the present invention is expressly designed to provide a new and sanitary construction of stocking for the use of infants exclusively. Accordingly, distinctive and 105 essential features of the invention are the structural details which provide for carrying out the sanitary function, namely a leg portion which terminates at a point adjacent the bottom line of the child's napkin 110 and the narrow attaching and supporting strip of substantially uniform width.

throughout, and so disposed as to provide an extended unobstructed napkin-receiving space above the top of the stocking at the back and at both sides thereof.

5 What I claim is—

A sanitary stocking for infants' wear consisting of a leg portion adapted to terminate at a point adjacent the bottom line of the child's napkin, and a single relatively 10 narrow attaching and supporting strip of substantially uniform width throughout

and joined with the extreme front of the upper edge of the leg portion, said strip being disposed parallel to the longitudinal axis of the stocking, and providing an extended unobstructed napkin-receiving space above the top of the stocking at the back and at both sides thereof. 15

LENA H. TAYLOR.
